M. A. B. STEIN

BOAT BUILDING BLOCK

Filed May 11, 1925

UNITED STATES PATENT OFFICE.

MILTON A. B. STEIN, OF BRIDGEPORT, CONNECTICUT.

BOAT-BUILDING BLOCK.

Application filed May 11, 1925. Serial No. 29,280.

To all whom it may concern:

Be it known that I, MILTON A. B. STEIN, a citizen of the United States, residing at Bridgeport, county of Fairfield, State of Connecticut, have invented a new and useful Boat-Building Block, of which the following is a specification.

This invention relates to toy blocks, and particularly to a set of blocks for building 10 toy boats or ships, and has for an object to provide a set of blocks which are simple in construction and may be made preferably of solid blocks of wood, and which may be easily and quickly secured together to build 15 toy ships of different types and sizes.

With the foregoing and other objects in view, I have devised the construction illustrated in the accompanying drawing forming a part of this specification, similar reference characters being employed throughout the various figures to indicate corresponding 20 elements. In this drawing,

Fig. 1 is a top plan view of a toy boat built of my improved blocks.

Fig. 2 is a side elevation thereof.

Fig. 3 is a top plan view of the stern blocks removed.

Fig. 4 is an end elevation of the stern blocks looking from the right of Fig. 3.

Fig. 5 is a side and end elevation of the key which may be used for assembling and disassembling the blocks, and

Figs. 6 to 13 inclusive illustrate some of the various combinations which may be 35 made with my improved blocks.

Referring to Figs. 1, 2 and 3 the boat shown is made up of a longitudinal central beam 15 about which the structure of the boat is assembled. At the forward end of

40 this beam is attached a pair of tapered blocks 16. These blocks are of the same shape and notched at the inner side of their larger ends, as shown at 17, to embrace the forward end of the central beam 15, and the

45 tapered sides of these blocks come to a point to form the bow of the boat. These blocks are secured on the opposite sides of the beam by means of a bolt 18 passing through aligned openings extending transversely

50 through the blocks and the beam. The openings in the blocks are preferably counterbored, as shown at 19, so that the head and nut of the bolt will be below the surface of the blocks when assembled. At the other 55 end of the beam is similarly fastened a pair of stern blocks 20. These blocks are of the

same shape but reversed, their rear ends being curved as shown, and they are notched on the inner side of the other end, as shown at 21, to fit the end of the beam 15. These 60 blocks are fastened to the beam by bolt 18 in transversely extending aligned openings 22 the same as the bow blocks. These blocks are also preferably undercut on their under sides as shown at 23, to give a more finished 65 effect to the stern end.

On the opposite sides of the beam 15 between the bow blocks 16 and stern blocks 20 are mounted a plurality of side blocks 24 which fill in the spaces between the bow and 70 the stern blocks. There are two rows of these blocks, one on each side of the beam, and two opposite blocks are secured to the beam by a transversely extending bolt 25 passing through aligned openings in the 75 beam and the blocks, these bolts being the same as the bolts 18. The openings in the blocks are counterbored, as shown at 26, the same as the bow and the stern blocks. This gives the body or hull structure of the boat. 80

A more finished and natural appearance may be provided by means of one or more cabin blocks 27 mounted on the top of this hull structure, as by means of bolts 28 extending vertically through this block and 85 the central beam 15, these openings being counterbored at their opposite ends for the heads and nuts of the bolts, as shown at 29, and also for mounting one or more masts 30 and one or more stacks 31. The lower ends 90 of the stacks and masts are preferably reduced as shown at 32 and 33, respectively so as to project into the counterbores 29 or the openings for the bolts 28 to mount them in 95 position.

In making the set it is intended to provide different lengths of center beams 15 and any desired number of side blocks 24, and as the structure of the boat is built about the central beam, by using different lengths of this beam and different numbers of blocks practically any length of hull may be constructed as desired, and by providing a plurality of cabin blocks 27 of different lengths and a plurality of masts 100 30 and stacks 31 a large number of different combinations and effects may be secured with these various blocks. A few of these combinations and effects are illustrated in Figs. 6 to 13, but there are numerous other combinations and effects which 105 may be secured with the same blocks at 110

the option of the child. These blocks, therefore, are much more interesting to the child because of the large number of different sizes, combinations and effects of ships which he may produce with them, and they give him an opportunity to exercise his ingenuity in devising different combinations and effects of different types of boats. At the same time the blocks are rigidly secured together but may be easily taken apart or assembled as the attaching means is an extremely simple one. The blocks may be made of any suitable material but are preferably made of wood painted as desired.

Having thus set forth the nature of my invention, what I claim is:

1. In toy blocks, a ship comprising a longitudinal central beam, blocks at the forward end of the beam to form the bow, 20 suitably shaped blocks at the other end of the beam to form the stern, side blocks on opposite sides of the beam to fill in the spaces between the bow and stern blocks, and means for detachably securing the blocks to the beam.

2. In toy blocks, a ship comprising a longitudinal central beam, tapered blocks at the forward end of the beam to form the bow, suitably shaped blocks at the other 30 end of the beam to form the stern, side blocks on opposite sides of the beam to fill in the spaces between the bow and stern blocks, a cabin block on the top side of the beam, and means for detachably securing the blocks to the beam.

3. In toy blocks, a ship comprising a longitudinal central beam, a pair of similar tapered blocks at one end thereof to form the bow, a pair of blocks at the other end 40 secured at the rear and undercut to form the stern, side blocks on opposite sides of the beam between the bow and stern blocks, and means for detachably securing the blocks to the beam.

4. In toy blocks, a ship comprising a longitudinal central beam, a pair of similar tapered blocks at one end thereof to form the bow, a pair of blocks at the other end

secured at the rear and under cut to form the stern, side blocks on opposite sides of the beam between the bow and stern blocks, a cabin block on the top side of the beam, means for detachably securing the blocks to the beam, a mast on the top of the beam, and a stack block on top of the cabin block.

5. In toy blocks, a ship comprising a longitudinal central beam, tapered blocks at the forward end of the beam to form the bow, suitably shaped blocks at the other end of the beam to form the stern, side 60 blocks on opposite sides of the beam to fill in the spaces between the bow and stern blocks, said blocks and beam having transverse aligned openings, and securing bolts passing through said openings.

6. In toy blocks, a ship comprising a longitudinal central beam, tapered blocks at the forward end of the beam to form the bow, suitably shaped blocks at the other end of the beam to form the stern, side blocks 70 on opposite sides of the beam to fill in the spaces between the bow and stern blocks, said blocks and beam having transverse aligned openings, a cabin block on the top of the beam, said cabin block and beam 75 having aligned openings, and securing bolts extending through said openings.

7. In toy blocks, a ship comprising a longitudinal central beam, tapered blocks at the forward end of the beam to form the bow, suitably shaped blocks at the other end of the beam to form the stern, side blocks on opposite sides of the beam to fill in the spaces between the bow and stern blocks, said blocks and beam having transverse 80 aligned openings, a cabin block on top of the beam having aligned openings counter-bored at their ends, securing bolts extending through the openings to secure the blocks to the beams, and a mast and a stack block having reduced ends to fit the openings in the beam and cabin block.

In testimony whereof I affix my signature.

MILTON A. B. STEIN.
